Inventor:
Henry H. Motschman
By Walter M. Full, Atty.

UNITED STATES PATENT OFFICE.

HENRY H. MOTSCHMAN, OF CHICAGO, ILLINOIS, ASSIGNOR TO UNION BED AND SPRING COMPANY, OF CHICAGO, ILLINOIS, A CORPORATION OF ILLINOIS.

HINGE.

Application filed August 17, 1925. Serial No. 50,561.

My present invention concerns certain features of novelty and improvement in hinge constructions, such as those used in folding beds, etc., but the new structure is capable 5 of advantageous employment in many different relations.

One object of the invention is the production of a hinge which has large bearing surfaces for two relatively-movable elements 10 and without depending for such surfaces on a hinge-pin or its equivalent.

A further aim of the invention is the provision of a hinge structure of this character employing hollow elements rockingly associated with one another in such a way that the hinge remains closed at all times and hence excludes the entrance of foreign matter to the hinge parts and gives the construction a neat and pleasing appearance under 20 all circumstances.

In order to enable those trained in this art to fully understand this invention both from structural and functional standpoints, in the accompanying drawing forming a part of 25 this specification, I have illustrated a present desirable and preferred embodiment of the invention and throughout the several views in this drawing like reference characters have been employed to designate the same 30 parts.

In this drawing:

Figure 1 is an elevation of the improved hinge structure;

Figure 2 is a vertical section on an enlarged scale, showing the parts in a different relation; and

Figure 3 is a fragmentary section on an enlarged scale on line 3—3 of Figure 1, the parts being viewed in the direction indicated by the arrows.

Referring to the plurality of views of the drawing, it will be seen that the one, hollow, male hinge-member, designated as a whole 11, square in cross-section, has a shorter side wall 12 equipped with a narrow, inturned flange 13 along its lower edge, the opposite wall 14 being longer and not supplied with such a flange.

The two side walls 15, 15, connecting the 50 two walls 12 and 14, are offset inwardly slightly, approximately the thickness of the metal of which the parts are made, along the curved lines 16, 16, the lower edges of such walls being curved at 17, and joining

the inner edge of the flange 13 with the bottom edge of wall 14.

Such inwardly-deflected sections of the two walls are each shaped to form an outstanding, hollow, circular rib 18 which inwardly of the structure presents a corresponding, annular groove or recess 19.

The complementary, hollow, female hinge-member, characterized as a whole 21, has a longer wall 22 supplied at its end with an inwardly-disposed flange 23 of substantially 60 the same width as the coordinate flange 13.

The opposite wall 24 is cut off at 25 and the two, side, connecting walls 26, 26 are cut off for a short distance at 27 in register with the edge 25, as is clearly depicted in 70 Figure 2, and they have a curved edge 28 joining the inner end of each margin 27 with the inner edge of the correlated flange 23.

The two terminal ears of the opposed walls 26, 26 are each pressed or formed to 75 provide an internal, annular channel 29 to receive the corresponding rib 18 with exactitude, the outer face of each such wall showing the complementary circular rib 31.

Hence the female hinge-member provides 80 proper seats for the ribs of the male hinge-member so that the two parts 11 and 21 may turn on one another on these ample bearing surfaces.

An insert or cover member 32 has a wall 85 34 secured, as by welding, brazing or the like, to the inner face of the wall 14 and from this projects a pair of arms 35, 35 apertured at 36 in register and in alignment with like-sized holes 37 and 38 in the overlapping 90 parts of the hinge-members and concentric with their circular hinge features.

These six, registering holes accommodate 95 a rivet 39 with opposite external heads or enlargements 41 and 42 permanently holding the parts of the hinge construction in correct assembled relation, but not constituting the usual hinge-pin whose function in this instance is largely performed by the interfitting, round ribs and complementary sockets. 100

Element 32 has a curved wall 43 extending from the edge of wall 34 and terminating in a flange 44 adapted, in the relation or position of the parts illustrated in Figure 2, to 105 overlie the companion flange 13, such part 43 comprising a cover or closure for the space which would otherwise occur between the two hinge-members, whereby to prevent the

entrance of dirt and other foreign matter which, in time, would tend to prevent a free and easy turning or rocking action of the hinge structure.

5 Many minor mechanical changes or modifications may be incorporated in the appliance illustrated and described without loss of its material attendant benefits and advantages and still come within the purview 10 of the invention as defined by the following claim.

I claim:

In a hinge construction of the character described, the combination of a hollow 15 hinge-member having a pair of spaced internal registering annular grooves, the walls of

said member having apertures therethrough a complementary hinge-member having a pair of spaced external registering annular ribs in said grooves, the walls of said second hinge-member having apertures therethrough concentric with said ribs, a cover-plate concentric with said grooves and ribs and having parts apertured in register with said other apertures, and means to maintain said 20 hinge-members in assembled relation and extended through the apertures of both hinge-members and those of said cover-plate parts.

In witness whereof I have hereunto set my hand.

HENRY H. MOTSCHMAN.
